SURGICAL CAST ANCHOR LOOP

Edward J. Hill, 1660 Lochridge, Bloomfield Hills, Mich.

Filed Dec. 23, 1963, Ser. No. 77,904

Term of patent 14 years

(Cl. D83—1)

FIG. 1

FIG. 2

FIG. 3

FIG. 4

FIG. 1 is an end elevational view of a surgical cast anchor loop embodying my new design; and

FIG. 2 is a side elevational view; and

FIG. 3 is a top view; and

FIG. 4 is a bottom elevational view.

I claim:

The ornamental design of a surgical cast anchor loop, substantially as shown.
